Primary Examiner — Elizabeth J Oswecki(74) *Attorney, Agent, or Firm* — Joe D. Calhoun; Rashauna A. Norment(57) **CLAIM**

The ornamental design for a globe gun vault, as shown and described.

DESCRIPTION

FIG. 1 is a right side elevation view of a globe gun vault showing my new design with the lid in an open configuration; the left side elevation view is a mirror image of the right side elevation view.

FIG. 2 is a left side elevation view of FIG. 1, with the lid in a closed configuration; the right side elevation view is a mirror image of the left side elevation view.

FIG. 3 is a rear elevation view of FIG. 1.

FIG. 4 is a front elevation view of FIG. 1.

FIG. 5 is a top plan view of FIG. 1.

FIG. 6 is a bottom plan view of FIG. 1; and,

FIG. 7 is a perspective view of FIG. 1.
